W. L. BROWN

PITMAN

Filed March 23, 1926

A technical drawing of a device, likely a vacuum chamber or similar apparatus. The drawing shows a central vertical tube with a flange at the bottom. Surrounding this tube are several concentric and irregularly shaped components, possibly gaskets or seals, labeled with numbers 11, 11a, 11b, 12, 13, 14, 15, 16, 17, 18, 19, 20, 21, and 22. The drawing is labeled 'FIG. 2.' at the top.

Attorney

UNITED STATES PATENT OFFICE.

WALTER L. BROWN, OF GRAVETTE, ARKANSAS.

PITMAN.

Application filed March 23, 1926. Serial No. 96,787.

This invention relates to a pitman.

It is generally aimed to provide a construction which is extremely durable and may be readily adjusted to compensate for 5 wear.

Another object is to provide a construction wherein the part subject to most wear may be metallic and the major portion or stock of which may be of wood in two 10 pieces to accommodate a shim.

While the pitman is adapted for general use, it is especially designed to supplant present constructions used on headers and binders, harvester threshers and mowers, 15 shaker arms of ordinary threshing machines, and the like.

One operative embodiment has been shown in accompanying drawings wherein:

Figure 1 is a side elevation of the pit- 20 man;

Figure 2 is a plan view thereof;

Figure 3 is a cross sectional view taken on the line 3—3 of Figure 1; and

Figure 4 is a view similar to Figure 2 25 with the parts disassociated and the stock without a shim.

Referring specifically to the drawings wherein like reference characters designate like or similar parts, the improved pitman is generally designated 10. It comprises a 30 stock 11 preferably of wood and in two halves 11^a as shown in Figure 1 to accommodate a shim 12 of wood, leather or the like when necessary to compensate for wear.

End sections are provided at 13 and 14. 35 The greatest wear in use is against these sections and accordingly they are preferably made of metal, usually bronze.

Said stock 11 and sections 13 and 14 are 40 held detachably but rigidly together by means of a U-shaped bolt 15, disposed partially in grooves 16 and 17 provided externally on the stock 11 and section 13, respectively. Said bolt passes through notches 12^a 45 in the shim to assist in holding the latter in place. The terminals of the bolt are screw threaded as usual and as shown and pass detachably through holes 18 in the section 14. Nuts 19 in pairs are secured on said

terminals, one of each pair constituting a 50 lock for the other.

In order to engage the wrist pins of machinery, the adjacent faces of the stock and sections are semi-circularly cut away to provide holes 20.

Oil may be supplied to the wrist pins or walls of said openings or holes 20 in any desired way as through diagonal holes 21 in the ends of stock 11.

In use the parts are attached by means of the bolt 15 to the wrist pins of the machinery, the latter being accommodated in holes 20 as is obvious. The nuts 19 provide for an adjustable connection. Wear in use will be slight on the metallic sections 13 and 14. 60 The wear, however, will be greater on the parts 11^a about the wrist pin holes as is known in practice, and in order to take up 65 this wear, the end walls of the stock may be cut or filed so as to reshape them, even a number of times, and when necessary, the stock 11 may have one or more shims disposed between the ends in order to give the pitman the proper length. A pitman constructed in accordance with the present invention will be exceedingly strong and durable and will greatly outlast existing constructions and effect a saving with respect to 70 time and cost in the upkeep thereof.

Various changes may be resorted to provided they fall within the spirit and scope 75 of the invention.

I claim as my invention:

A pitman composed of a wooden stock, end bearing sections therefore of metal, said 80 stock and sections being cut away to provide wrist-pin-engaging holes, a U-shaped bolt marginally surrounding one of said sections and said stock, the latter section and stock having exterior grooves entered 85 by the bolt, and the other section having holes accommodating terminals of said bolt, the stock being in sections, and a shim between the sections having notches engaged by said bolt.

In testimony whereof I affix my signature.

WALTER L. BROWN.
